Thomas Isaac Wallis

By

G. R. Hendry, Atty.

UNITED STATES PATENT OFFICE

THOMAS ISAAC WALLIS, OF EVANSVILLE, INDIANA

PORTABLE FOLDING TABLE

Application filed July 29, 1929. Serial No. 381,841.

This invention relates to portable folding tables adapted for indoor or outdoor use, wherein the table top comprises foldable sections carrying foldable legs.

5 My object is to provide a foldable table of improved construction which can be quickly and easily folded into very compact condition in flat form, enabling the table to be readily carried from place to place and permitting 10 easy stacking and packing or storage of a large number of the tables.

A further object is to provide an improved folding table having a sectional top, of which certain of the sections carry improved foldable legs, the arrangement being such that the top sections may be extended out to form the complete table top, and the top sections and legs locked in position, or, the sections may be folded to completely enclose the legs 20 for purposes of arranging the table in compact form, as aforesaid.

While I have illustrated a practical embodiment of the invention in the accompanying drawings, and hereinafter described said 25 embodiment, I am well aware that the leg construction might be modified according to the use to which the invention is to be put, further, that the table may be constructed of wood or metal; also, modification may be 30 resorted to in adapting the table to any particular indoor or outdoor use, without departing from the mechanical principles involved. Therefore, I do not limit the invention to the precise construction hereinafter 35 described and which is shown in the accompanying drawings, wherein:

Figure 1 is a cross-section, taken through one of the end sections of the table top, the table being in set-up condition;

40 Fig. 2 is a longitudinal section, the table being set up;

Fig. 3 is a perspective view, showing the table completely folded; and

Fig. 4 is a bottom view, the legs being folded but the top sections being open.

The top comprises a center section 1 and end sections 2, the end sections being hinged to the center sections at 3, in any suitable manner so that when the end sections are 50 folded as shown in Fig. 3, the legs are en-

closed within the sections and the entire table has a compact, flat form making it very convenient to carry it about, or to stack large numbers of the tables in a small space whether they are put in storage or are crated, or are 55 being transported in quantity.

The apron parts 4 of the sections of the table are provided with holes 5, of which two appear in Fig. 3, for the reception of a tie rod 6, Fig. 2, for holding the said sections in extended position, it being understood that all of the holes 5 are in alinement. The tie rod 6 may be jointed so that when folded, it will lie inside of the folded table when in the condition shown in Fig. 3. 65

The table is supported by legs 7 which are carried by the end sections 2, said legs having triangular looped parts 8 which are hinged in metal pieces 9 and secured by suitable fastenings 10 to the under side of the 70 sections 2.

The lower parts of the legs 8 are encircled by eyes 11 of braces 12, said braces also having eyes 13 which receive the tie rod 6 when the table is in the extended condition 75 shown in Figs. 1 and 2.

The legs 7 and braces 12 are adapted to fold into the sections 2 as shown in Fig. 4 and the said sections may then be folded over the section 1. Any suitable locking 80 means may be provided for securing the sections in their folded condition and, if desired, any suitable handle may be used for attachment to the table when in its folded condition so that it may be carried from 85 place to place, as for instance, when it is used as a camp table.

When the sections are opened out, the legs may be let down, and the tie rod 6 run through the holes 5 and through the eyes 90 13 of the braces, whereupon the table is arranged as shown in Figs. 1 and 2, the sections being locked and the legs securely locked and braced.

When the table is folded as shown in Fig. 95 3 the folded legs are completely housed and concealed by the table top sections 1 and 2.

What I claim is:

In a portable folding table, the combination with a center top section and end top 100

sections hinged to said center section and foldable against the same side thereof, of a pair of foldable legs hinged to, and bodily carried by, each end section, a brace hinged to each leg, and a releasable tie rod engaged with all of the top sections and with all of the aforesaid braces to lock the top sections and the legs in extended position.

10 In testimony whereof I affix my signature.
THOMAS ISAAC WALLIS.
